R. L. LOWMAN

DETONATING FUSE

Filed June 18, 1921

UNITED STATES PATENT OFFICE.

ROY L. LOWMAN, OF BUCKHANNON, WEST VIRGINIA, ASSIGNOR OF ONE-HALF TO
HARRY C. DODGE.

DETONATING FUSE.

Application filed June 18, 1921. Serial No. 478,739.

To all whom it may concern:

Be it known that I, ROY LEIGHTON LOWMAN, a citizen of the United States, residing at Buckhannon, in the county of Upshur 5 and State of West Virginia, have invented certain new and useful Improvements in Detonating Fuses, of which the following is a specification.

This invention relates to detonating fuses, 10 and has for an object to provide a fuse producing a lag, or an interval of time, between concussion and detonation.

A further object of the invention is to provide a detonating fuse having a safety 15 interrupting member interposed between the initial detonating charge, ignited by a percussion cap, and the ultimate detonating charge or ignitor, such safety device being held in safety position until after the fuse, 20 with its projectile, has been fired from the gun.

With these and other objects in view, the invention comprises certain novel elements, 25 units, parts and combinations as will be hereinafter more fully described and claimed.

Referring to the accompanying drawings, 30 which are made a part hereof and on which similar reference characters indicate similar parts,

Figure 1 is a longitudinally diametrical sectional view through the fuse.

Figure 2 is a transverse sectional view taken on line 2—2 of Figure 1.

Figure 3 is an inclined transverse sectional view taken on line 3—3 of Figure 1.

Figure 4 is a perspective view of the safety interrupter.

Like characters of reference indicate corresponding parts throughout the several views.

The improved fuse, which forms the subject matter of this application, is adapted to be associated with a projectile of any usual and ordinary type, adapted, after the projectile is fired from the gun, to automatically set the parts to be ignited, and to in turn ignite the charge of the projectile, upon the impact of the projectile with an object, provide for a delay or lag between instant of concussion and the instant of detonation, to permit the projectile to penetrate into the impinged object. For the purpose of associating with the projectile, the

fuse comprises a base 10 having screw 55 threads 11 for engaging a screw threaded opening in the projectile with a head 12 to engage against the surface of the projectile. Openings 13 are provided for engagement with spanner for placing the fuse. 60

To the base 10 the shell 14 is secured, in any approved manner, as by screw threaded engagement at 15. Intermediate the ends of the shell 14 a threaded constriction 16 provides seating for a threaded member 17 65 which in turn carries the anvil 18 upon which is normally positioned the percussion cap 19.

Within the shell 14 is also mounted to slide, the hammer 20 held normally at its 70 inoperative limit by the spring 21. The hammer 20 carries the firing point 22 pivoted at 23 with a weight 24 subject to centrifugal force as will be hereinafter more fully explained. The firing apparatus, comprising 75 the hammer, the firing pin and its associated parts, is not novel in the present disclosure and separately and individually form no part of the invention.

The member 17 is provided with an initial 80 detonating charge 25 and with a sinuous passage between such charge and the percussion cap 19. The exact formation of the sinuous passage is immaterial but that shown at Figure 2 has been found to be 85 satisfactory, comprising a terminus 26 communicating with the charge 25 and a terminus 27 opening through the partition 28 and communicating with a substantially similar sinuous passage, having a terminus 29 90 communicating with the charge 30 immediately in engagement with the percussion cap 19. The sinuous communicating passage between the charge 30 and the charge 25 may be left vacant or may be filled with ignitable material. If ignitable material is used it is preferably the same as the charge 95 30, which, for convenience will be called black powder. If left vacant the fire from the charge 30 must pass through this sinuous passage and ignite the charge 25. The same would follow if the sinuous passage is filled with ignitable material. In any event by reason of the length and sinuosity of the passage, traversing such passage will be 100 slightly delayed whereby there will be a perceptible interval of time between the ignition of the charge 30 and the charge 25.

100

105

Wherever required closures are employed, the equivalent of a "wad" as for instance at 31.

The charge 25 communicates with a passage 32 which, except for the interrupting features hereinafter described, communicates directly with the final detonating charge or "booster" 33. The latter is confined by the screw plug 34 which is blown out by the 10 explosion of the detonating charge 33 and the charge of the projectile into which the fuse is inserted is thereupon and thereby ignited. The passage 32 may be filled with detonating material similar to that of the booster 33, such as tetryl.

The interrupter for the passage 32 comprises a plug 35 having passages 36 positioned to at times establish communication between the normally separated sections of 20 the passage 32, to be normally held by the spring 37 so that the plug 34 completely closes the passage 32 and isolates the charge 33 from the charge 25 so that in case of the accidental ignition of the charge 25 the passage 32 being closed expansion is provided in the chamber 38 surrounding the charge 25 and the chamber 39 containing the spring 21, and is not communicated to the charge 33.

The plug 35 is provided with an enlarged 30 and correspondingly weighted head 40 reduced to form a shoulder 41. So long as the detent 42 maintains its normal position the plug 35 can not be removed from its closing position across the passage 32.

35 The plug 35 being carried normally in advance by the projectile, the inertia of the detent 42 causes the said detent to slide against the tension of its spring 43 whereby the shoulder 41 is released permitting centrifugal force to act upon the head 40 for the purpose of unclosing the passage 32. When acceleration of the projectile has ceased, so that the inertia no longer acts upon the detent 42 the spring again forces the detent forward under head 40 and holds plug 35 in firing position. By this time, however, the centrifugal force has moved the plug 35 to bring the passages 36 into register with the passage 32 and the plug 35 45 is locked in open position by the detent 42.

50 At the same time centrifugal force acting upon the weight 24 has swung the firing member upon its pivot 35 so that the firing pin 32 is in alignment with the percussion cap 19. The inertia of the hammer 20 as well as the tension of the spring 21 holds the firing pin out of engagement with the cap. At the impact of the projectile with an object the momentum of the hammer 55 overcomes the tension of the spring 21 and, inertia no longer acting, the firing pin 32 is brought into firing concussion with the cap.

60 It will be seen therefore that a projectile 65 may be provided with this fuse, and may

be handled with impunity, as it is not possible to fire it without the combined action of centrifugal force from the rapid rotation of the projectile and the inertia of the detent 42 owing to the acceleration of the 70 projectile. Neither one or the other of these forces would be at all likely to result from the handling of the projectile, but the combination of both, under any other condition than that of being fired from a gun, is 75 impossible. As centrifugal force begins to act before emergence of the projectile from the gun and as acceleration continues only until shortly after emergence, it is obvious that almost instantaneously after being fired 80 from the gun the parts are in position for firing immediately upon impact but that until all of such contingents are combined ignition is impossible and a projectile, provided with such fuse, is safe for handling 85 and transportation. This removes the necessity of transporting and handling projectiles and fuse separately, to be combined only at the time of loading.

Having thus fully described my said invention what I claim as new and desire to secure by Letters Patent is:

1. A detonating fuse comprising a detonating charge and an igniting charge, an igniting element, a sinuous passage between the igniting element and the igniting charge, means closing communication between the igniting charge and detonating charge adapted to be withdrawn by the force generated by the trajecting of the fuse 95 and a single detent for locking said means in either the closed or withdrawn position, substantially as set forth.

2. A detonating fuse comprising a shell having a detonating charge and an igniting charge, a separating member interposed between the charges and provided with a passage, an interrupter extending across and closing the passage and provided with a weighted portion eccentric to the axis, a 105 detent locking the interrupter in two positions thereof and subject to movement relative to the fuse through its inherent inertia, and means to fire the igniting charge at impact.

3. A detonating fuse comprising a detonating charge and an igniting charge, a passage therebetween, an interrupter operating across the passage and provided with a bore, a spring within the bore, said interrupter having at one end a transverse passage which at times is aligned with the first said passage to provide unrestricted communication between the two said charges, said interrupter also having an enlarged 110 weighted portion, a detent at times bearing against the under side of said enlarged portion and at other times bearing against the upper side of said enlarged portion, substantially as set forth.

4. A fuse comprising a shell having a detonating charge and an igniting charge, a separating member between the charges provided with an oblique communicating passage and a cylindrical recess intersecting the same and perpendicular thereto, a cylindrical plug in the latter passage having an enlarged base with an annular flange and subject to the action of centrifugal force, and a detent adapted to engage either above or below said base, substantially as set forth. 30
5. A fuse comprising a shell having a detonating charge and an igniting charge, a separating member between the charges provided with an oblique communicating passage and a cylindrical recess intersecting the same perpendicular thereto, a cylindrical plug in the latter passage and having a plurality of angularly related transverse passages at its inner end and adapted to be moved by centrifugal force to open the first named passage, and means for locking the plug in either advanced or 20 retracted position, substantially as set forth.
- 25 6. A fuse comprising a shell having a detonating charge and an igniting charge, a separating member between the charges provided with an oblique communicating pas-
- sage, a transverse recess intersecting the same and perpendicular thereto, a plug normally closing the passage and adapted to be withdrawn by centrifugal force, substantially as set forth. 35
7. In a fuse for projectiles the combination of a shell, having a forward chamber for a bursting charge, a separator in rear thereof having a longitudinal channel, a plug normally closing the passage and automatically removed therefrom after discharge 40 of the projectile, a member spaced from said chamber by the separator said member having chambers at the front and the rear for a detonating charge, and a tortuous passage connecting them, said rear chamber 45 also having means to support a percussion cap in communication with one chamber, and a slideable and swingable firing point adapted to be positioned by centrifugal force and to strike the cap on impact of the 50 projectile, substantially as set forth.

In witness whereof, I have hereunto set my hand and seal at Washington, District of Columbia, this 17th day of June, A. D. nineteen hundred and twenty-one.

ROY L. LOWMAN. [L. S.]

Witness:

E. W. BRADFORD.
